DRESS

Rose N. Choolfain, Belmont, Mass.

Application October 11, 1956, Serial No. 43,313

Term of patent 3½ years

Cl. D3—26)

The dominant feature of the invention rests in the combination of the wing like cuffs, alternate tuck and gores in the skirt, and lowered pleat in the rear of the bodice in a dress of the type shown.

I claim:

The ornamental design for a dress as shown and described.
